UNITED STATES PATENT OFFICE.

SIGURD OLSON, OF PORTLAND, OREGON.

HIGH-COMPRESSION TWO-CYCLE INTERNAL-COMBUSTION ENGINE.

Application filed April 15, 1926. Serial No. 102,191.

The object of my present invention is to provide, in one simple and efficient unit a balanced internal combustion engine of the two cycle type and at the same time in an elongated cylinder at each down stroke of the piston compress a charge of air, the said compressed charge of air to be stored under pressure in an air receiver, the same to be used while under compression for admission into the combustion chamber while under compression, and mixed and heated with a supply of fuel for combustion purposes.

Further objects of my invention consist in supplying heating means for heating the mixed charge of compressed air and fuel and the final admission of a further supply of compressed air for fuel purposes.

Still further objects of my invention consist in the admixture of compressed air and a carboniferous fuel and the heating of the same before use. A sufficient quantity of the same being heated in advance of use to provide adequate time for the volatilization of the entire content of the mixture.

A still further object of my invention consists in providing a simple device wherein the same is free from the admission of the products of combustion into the crank case of the device.

Still further objects of my invention consist in the construction of a simple and efficient device, free from many of the complications usually encountered in similar devices and in one wherein the inexperienced may operate the same and yet derive a high efficiency from the fuel as an operating medium.

With these and incidental objects in view, the invention consists in certain novel features of construction and combination of parts, the essential elements of which are set forth in the appended claims and a preferred form of embodiment of which is hereinafter shown with reference to the drawings which accompany and form a part of this specification.

In the drawings:

Fig. 1 is a side elevation partially in section of an assembled unit of the four cylinder type.

Fig. 2 is a vertical cross section view, taken on line 2-2 of Fig. 1, looking in the direction indicated.

Fig. 3 is a cross section view of the atomization valve wherein the compressed air is expanded through a nozzle and in doing so

the fuel products are picked up and carried therethrough and delivered to the heating coil not here shown.

Fig. 4 is a cross section view of the throttle valve to be placed adjacent the intake manifold disposed adjacent the operating cylinders.

Fig. 5 is an end view, taken on line 5-5 of Fig. 4, looking in the direction indicated.

Fig. 6 is a diagrammatical lay out of the explosion and compression cylinder, the piping connection leading to the compressed air storage tank, the fuel storage tank, the mixing and throttle valves and the piping connections incident thereto.

Like reference characters refer to like parts throughout the several views.

1 is the motor block, and 2 is the motor base upon which the motor block is superposed and to which the same is secured by suitable fastening means. The crank case is shown at 2^a. 3 is the main crank disposed within suitable bearings within the motor base. Suitable guideways 4, are disposed within the block upon which the cross head operates and the purpose of which is to maintain alignment with the block. The connecting rod is shown at 5. A cross dia-

phragm 5^a is disposed within the lower end of the cylinder and a hub or bearing 6 is disposed central thereof through which the piston rod 8 passes. A suitable gland 7 is disposed about the piston rod and maintains a tight connection between the piston rod and the gland to prevent leakage therearound and therethrough. The cross head 7^a operates upon the guideways 4 and maintains the piston rod in alignment. Suitable

removable and adjusting shims are disposed within the cross head to compensate for wear and adjustment. The piston has a central cross diaphragm 10 into which the piston rod is made to engage as in a threaded connection, as illustrated at 13. Because of the upper end of the piston taking the explosion thrust and the lower end the thrust of compression, I have provided two heads in the piston, one at either end, as shown at 11 and 12. For the purpose of the piston being maintained in a cool condition and for the further purpose of lightening the same when the adequate length is obtained, I have provided an air space disposed between the cross diaphragm and either head of the piston, this space is as shown at 14 and 15 in

Fig. 2. The cylinder is jacketed by the usual

water cooling system disposed about the outer walls of the cylinders. Air is compressed within the lower end 16 of the cylinder and passes out through suitable discharge ports and is conducted through piping 17 to the air receiver and tank 18, which may be placed at any suitable location and of a size adequate to the service and type of engine with which it is being used in conjunction. The inlet port 19 admits air for compression to the compression cylinder 16. Where it is found desirable to conserve all heat and prevent loss thereof the piping 17 and the tank may be insulated by any suitable means to prevent the free flow of heat therefrom. A fuel supply tank 20, is disposed within the piping circuit and is connected with the valve 24, by suitable piping connections as shown at 21. Piping 22 connects the air storage tank 18 with the valve 24 on its one side terminating in an expansion nozzle within the primary mixing valve 24. A detail of the valve is as shown in detail in Fig. 3. A chamber 23 is disposed within the body of the valve into which the piping connection 22 enters and the suction caused through the passage of the air under compression across the chamber 23, causes a passage of the fuel as gasoline or other fuel to enter into the stream flow and to enrich the same. The piping connection 23^a enters the chamber 23, opposite the nozzle terminal of the pipe 21. I have found most economical results may be obtained wherein the compression of the air disposed within the air tank or receiver is between fifteen pounds minimum and seventy-five pounds maximum. Where liquid fuel is being used as the source of energy supply, the same is picked up as a liquid and enters the chamber 23, as a liquid from where the same is mixed with the compressed air and the same is volatilized. To further increase this volatilization and to expand the same into vapor, I pass the pipe 23^a as a coil 26 about the exhaust manifold 25, of the motor as shown in Fig. 1. This coil should be of substantial length to thoroughly heat the pipe coil 26, and to act as a storage supply for the mixed and vaporized fuel. A hood 27 is disposed about the coil which should be covered with an insulating covering to conserve the heat imparted to the coil from the exhaust manifold. The heated and mixed fuel supply is then conducted through pipe 28 and enters the throttle inlet valve 29, which is shown in detail in Fig. 4, wherein a second compressed air supply is admitted to the chamber 30 disposed therein which is connected to supply pipe 31 connected directly with the air supply storage tank 18. This pipe 31 has a valve 32 disposed therein in advance of the entry of the pipe 28 to the valve 29. The valve 29 connects the fuel and air supply to the inlet

manifold 33 from where the mixed air and fuel enters the various cylinders of the prime mover. Disposed within the chamber 30 of the inlet valve 29 is a throttle valve 34, the object of which is to permit of manual manipulation of the valve and to a further manual manipulation of the mixture of the air and fuel supply being admitted into the inlet manifold from where it is drawn into the cylinders for fuel.

To facilitate the adjustment of the gland nut 7, and to further provide for the inspection and adjustment of other parts of the motor I have provided removable inspection plates 36, which are disposed through the wall structure and which are secured thereto by suitable fastening means.

A system of this type may be connected to motors of the present type by the use of an auxiliary air compressor to compress the air and a storage tank for storing the same for use in valves as herein outlined.

Applicant is aware that heretofore compressed air has been used to increase the weight of the charge of fuel and to increase the power output of the engine and therefore disclaims any matter relating thereto, but applicant is unaware that compressed air of a pressure of several atmospheres has been used while in a warmed state for the admixture of carboniferous fuel therein, then being heated and the final admixture of compressed air before the entry of the same into the cylinders for power purposes. Applicant is further unaware that the cylinder of the prime mover has been used as the compressor for the compressing of the air to be used.

While the form of mechanism herein shown and described is admirably adapted to fulfill the objects primarily stated, it is to be understood that it is not intended to confine the invention to the one form of embodiment herein shown and described, as it is susceptible of various forms, all coming within the scope of the claims which follow:

What I claim is:

1. In a high compression two cycle internal combustion engine, the combination with an internal combustion engine provided with a precompression chamber formed opposite the explosion chamber, and having a compressed air storage tank connected to said precompression chamber; of a primary mixing valve connected to said storage tank and to a fuel supply tank; an inwardly extending nozzle formed within said mixing valve and disposed above the fuel inlet into said valve and disposed at the compressed air inlet; a secondary mixing valve mounted to the intake manifold of said engine; piping connecting both said valves; and means formed in said last mentioned piping intermediate said valves to heat the mixture passed therethrough.

2. In a high compression two cycle internal combustion engine, the combination with an internal combustion engine provided with a precompression chamber formed opposite the explosion chamber, and having a compressed air storage tank connected to said precompression chamber; of a primary mixing valve connected to said storage tank and to a fuel supply tank; a secondary mixing valve mounted to the intake manifold of said engine; piping leading from the first valve to the second valve; said secondary mixing valve being also directly connected to said compressed air storage tank; an inwardly extending nozzle formed within said secondary mixing valve connected to the inlet from said storage tank, and extending beyond and at an angle to the inlet from the primary mixing valve; and the piping leading from the first valve to the second valve being spirally disposed about the exhaust manifold of said engine.
3. In a high compression two cycle internal combustion engine, the combination with an internal combustion engine provided with a precompression chamber formed opposite the explosion chamber, and having a compressed air storage tank connected to said precompression chamber; of a primary mixing valve connected to said storage tank and to a fuel supply tank; an inwardly extending nozzle formed within the primary mixing valve connected to the inlet from said compressed air storage tank, and extending beyond and at an angle to the inlet from the fuel supply tank; a secondary mixing valve mounted to the intake manifold of said engine; piping leading from the first valve to the second valve; said secondary mixing valve being directly connected to said compressed air storage tank; an inwardly extending nozzle formed within the secondary mixing valve connected to the inlet from said storage tank, and extending beyond and at an angle to the inlet from the primary mixing valve; a rockable throttle valve mounted within the secondary mixing valve and disposed between the intake manifold and the inlets from the air storage tank and the primary mixing valve; and the piping leading from the first valve to the second valve being spirally disposed about the exhaust manifold of said engine.

SIGURD OLSON.
